DOLL

Russell A. Abbott, Akron, Ohio, assignor to Johnny Appleseed Food Products Corporation,
Columbus, Ohio, a corporation of Ohio

Application February 25, 1954, Serial No. 29,216

Term of patent 14 years

(Cl. D34—4)

To all whom it may concern:

Be it known that I, Russell A. Abbott, a citizen of the United States and resident of the city of Akron and State of Ohio, whose Post Office address is 421 Kathleen Avenue, Akron 3, Ohio, have invented a new, original, and ornamental Design for a Doll, of which the following is a specification, reference being had to the accompanying drawing, forming a part hereof.

In the drawings the vertical lining in the area of the mouth and on the object clasped in the right hand indicates the color red.

I claim:

The ornamental design for a doll, as shown and described.
